APPARATUS FOR SUPPLYING INK IN
PRINTING PRESSES

Thomas Padula, Jersey City, N. J.

Application May 5, 1937, Serial No. 140,796

5 Claims. (Cl. 101—356)

This invention relates to inking means and to means and methods for applying ink on type in printing presses and more particularly to apparatus and devices for distributing ink on inking rollers and applying it to type on reciprocating beds.

One object of the invention is to provide an improved vibrating means for vibrators or distributing rollers for form-inking rollers.

10 Other objects of the invention are to provide an improved device of this kind which will apply ink to a wide area of type with a minimum of type-bed travel and distribute the ink evenly without increased wear and tear on the press.

15 Additional objects of the invention are to improve generally the simplicity and efficiency of such methods and apparatus and to provide an extremely simple easily adjusted distributing apparatus of this kind, free of gears, which is economical, durable, and reliable in operation, economical to manufacture and install, and will not cause loss of speed to the press.

20 Still other objects of the invention will appear as the description proceeds; and while herein details of the invention are described, the invention is not limited to these, since many and various changes may be made without departing from the scope of the appended claims, interpreted as broadly as is consistent with the state 25 of the prior art.

The inventive features for the accomplishment of these and other objects are shown herein in connection with an improved inking device which briefly stated, is shown in combination with a 30 press having a printing roller under which a type-carrying bed reciprocates to bring the type thereon into engagement with paper carried around by said roller. The usual fountain-supplied inking rollers are disposed near one side of the printing roller for engaging and supplying ink to type on the intermediate part and one end part only of the bed while my improved supplemental inking device is disposed near the other side of the printing roller for picking up ink from type on 35 intermediate parts of the bed and applying said ink to type at the outer end of the bed, to cause thorough ink distribution and allow printing from all parts of the bed, thus increasing the effective length of the bed without increasing the 40 length of the press frame. In practice, the ink thus picked up and distributed by the supplemental device may be supplied entirely by the ink supplied to the type by the regular rollers.

45 My improved device may be supplied in various forms. For instance, the device may comprise a pair of brackets disposed on opposite sides of the press and carrying upper and lower journal bearings, the lower bearings carrying parallel form rollers which rotate back and forth 50 as the type on the bed reciprocates. A vibrator

5 roller rests on said form rollers and is rotated by gears from a rack on the bed. The vibrator is provided with shafts rotary in the upper bearing, the shaft at, at least, one end being threaded and received in an internally threaded bushing 5 yieldably rotatable in the adjacent upper bearing and normally yieldably held against rotary movement, whereby the rotating distributor is moved longitudinally back and forth as it rotates back and forth.

10 Stop collars secured on the vibrator shaft a short distance from the sleeve, with the bushing therebetween, are each provided with a projection engageable with an adjacent lug on the adjacent end of the bushing thereby to rotate the 15 bushing with the threaded shaft to cause longitudinal movement of the shaft to cease, thereby to confine such movement to convenient limits.

Additional control means may be provided for raising the inner form roller during and just 20 after the pause of the bed at its outward limit, to prevent leaving a heavier ink zone at such pause, said inner form roller lowering in time to remove any heavier ink zone that may have been left by the outer form roller.

25 In the accompanying drawings, Fig. 1 is a fragmental side elevation showing an end of a press to which my device is applied;

Fig. 2 is a plan showing the press bed;

Fig. 3 is an elevation showing the sides of the 30 inking rollers and vibrator of the device;

Fig. 4 is a transverse vertical sectional view, partly in elevation, showing the relation of the rollers of the device;

Fig. 5 shows a section taken substantially on the line 35—5 of Fig. 3;

Figs. 6 and 7 are respectively side elevations, partly in section, and end elevation of one of the vibrator gears and its bearing bracket;

Fig. 8 is an elevation partly in section showing 40 the side of the inner form roller and parts of said control means;

Fig. 9 is an elevation of parts of said control means; and

Fig. 10 is a transverse sectional view of the 45 form rollers and vibrator showing the inner form roller as slightly raised by said control means.

50 My invention is shown in combination with a Kelly press comprising side frame members 10 having longitudinal bed tracks 11 (Fig. 3) thereon supporting a bed 12 reciprocator under a transverse printing roller 14 mounted on the frame, said bed having a lower rack 15 along a side edge engaged by a bed-driving gear 16 (Fig. 1) for reciprocating the bed to bring the type 17 55 (Fig. 4) thereon into engagement with paper presented to the roller at the path 18 and carried around by said roller and discharged along the path 19. The ink fountain 20 supplies ink to rollers 21 which in turn supply it to inking rollers 60

- 25 near the inner side of the printing roller, and engaging type on the bed as the bed moves inwardly during printing. On the Kelly press the bed moves inward (rightward on Fig. 1) far enough to ink the type at the inner end margin 26 (Fig. 2) and the intermediate portion 27 of the bed, but not far enough inwardly to engage marginal type at the extreme outer margin 28 of the bed.
- 10 The supplemental inking device 30 (Fig. 1) is disposed near the outer side of the printing roller 14 and picks up ink from type on intermediate parts 27 of the bed and applies it to marginal type at 28 to allow printing from all parts of the bed, 15 thus greatly increasing the effective length of the bed 12 without increasing the length of the press frame 10.

Said device 30 comprises a pair of roller brackets 32 which are secured, by bolts 33 (Fig. 3), 20 opposite to each other on the respective side frame members 10 near the outer side of the printing roller 14, each bracket comprising upstanding inner and end guide-members 35, 36 disposed in a row along the side frame member, and forming 25 upright middle and end slots 37, 38, the middle slot 37 being the tallest.

Upper and lower roller sockets or journal blocks 40, 41 are vertically adjustable in said middle and end slots 37, 38 respectively and are provided with 30 flanges 42 (Fig. 5) for holding the blocks in place. The lower sockets 41 are held in adjusted position by adjusting set screws 44 engaged thereunder and support a pair of parallel form rollers 45 adapted to engage the type and each provided 35 with an axial roller shaft 46 (Fig. 3) engaged at each end of the roller in corresponding journal blocks 41.

A bearing bracket 48, 49 (Figs. 3, 6 and 7) having a lower flange 49 mounted fast on the inner 40 face of one of the roller brackets, comprises a large tubular bearing portion 48 spaced coaxially around the adjacent end of one of the roller shafts, 46, and is provided with an outer annular shoulder 50 and adjacent reduced portion 51 forming an outer cylindrical bearing face rotatably receiving a large ring gear 52 against said shoulder 50. A retaining collar 53, secured on the outer margin of said reduced portion, holds said gear in place.

50 An engagement means such as a rack 55 (Fig. 2) carried on an adjacent side member and an extension 56 alined therewith on the side of the bed engages said ring gear 52, during the outer and extreme inner movements of the bed, thereby to rotate the ring gear back and forth as the bed reciprocates. A vibrator or distributor roller 57 resting on said form rollers 45 is provided with axial or end shafts 58 rotary in said upper sockets 40, one end of said vibrator 57 being provided 55 with a wide gear 59 meshing with said ring gear, whereby the vibrator is rotated back and forth by the ring gear, at various positions of longitudinal movement of the vibrator, to be hereinafter explained.

At least one end shaft 58 is provided with 60 threads 60, at least one upper socket or journal block 40, the one at the thread 60, has a large bore 62 (Fig. 5) receiving an internally threaded externally cylindrical bushing 63 engaged on the 65 threads of said shaft 58 and disposed in, and at times rotary in, said large bore, and provided at one end with an end flange 64 provided with a lug 65 on its outer end face. A nut 66 secured on the other end of the sleeve by a set screw 67 is also 70 provided with a lug 68 on its outer end face.

A friction washer 70 between said nut and block assists in yieldably holding the sleeve at times against rotation, thereby to cause the vibrator to travel longitudinally in one direction or the other, depending upon its direction of 5 rotation.

Stop collars 72, 73 are adjustably secured by pins on the vibrator shaft near the ends of the threaded portion a distance apart about as great as the length of the sleeve plus the distance of 10 longitudinal travel of the distributor; and each collar is provided on its face toward the sleeve with an inner lug or projection 74 engageable, the one or the other, with the adjacent lug 65 or 68 as the vibrator moves longitudinally and as a 15 collar moves toward and reaches the lug. This causes the sleeve 63 to overcome the friction and rotate with the threaded shaft 58 and stop the relative rotation between the threaded shaft and the sleeve, thereby stopping endwise movement 20 of the vibrator, thus to limit such movement to the extent desired.

A latch plate 76 pivoted on a screw 77 on the top face of an inner upstanding member 35 of each bracket is provided with a lateral recess 78 at its free end to receive a clamping screw 79 on the adjacent inner member 35 for clamping the latch plate to the bracket. An adjusting screw 80 passes downwardly through the latch plate and bears on the journal block 40 of the vibrator, 30 to give the latter the proper pressure against the form roller 45. When it is desired to remove the vibrator, the screw 79 is unclamped and the plate 76 pivoted to remove the plate and screw 80 entirely away from the space 37, whereupon the vibrator and blocks 40 may be removed upwardly 35 from the brackets.

The operation will be easily understood from the foregoing. Usually it is desirable to apply a small amount of ink to the distributor. Reciprocation of the type bed carries the type back and forth under the rollers 25 thus applying enough ink to the type at 26 and 27 (Fig. 2), but not any at the edge portion 28. As the portions 27 pass under the rollers 45, these rollers pick up ink 45 which, through the operation of these rollers and the vibrator, is transferred to type at the edge portion 28.

Reciprocation of the bed, and rack 55, 56 rotates the gears 52 and 59, and therefore also the 50 roller 57 with its shaft, and the two form rollers. The friction acting on the sleeve 63 holds the sleeve against rotation at intermediate positions of the longitudinal movement of the vibrator, and causes the threaded shaft 58 to move in one longitudinal direction or the other, depending upon the direction of rotation, until a predetermined limit of movement (depending on the position of adjustment of the collars 72, 73 but not greater than the width of the gear 59) is reached, whereupon the engagement of the lugs 74 causes the sleeve to rotate with the threaded shaft so that longitudinal movement of the vibrator ceases until the direction of rotation is reversed. Longitudinal movement of the vibrator then takes place 65 in the opposite direction until the lug of the opposite collar is engaged. The wide gear 59 allows this movement to take place without unmeshing from the ring gear 52.

The above operation is repeated at each reversal of movement of the bed, thus vibrating the vibrator and causing an even distribution of ink on the rollers 45.

It is stated above that a small amount of ink may be initially supplied to the vibrator roller. 75

This is not absolutely necessary, as the form rollers pick up ink from the intermediate type and transfer it to the outer end type. On the other hand ink may be supplied at intervals or continuously to the vibrator roll by hand; or a fountain as at 28 in Fig. 1 may be provided for the vibrator roller or to other forms of inking means at the outer end part of the press.

The rollers 45 are disposed over the type during the necessary pause when the bed reverses from outward to inward movement. If the rollers 45 rest upon the type during this pause, they might leave more ink on the type at the point of contact, which might cause a darker zone across the printed sheet. To prevent this, control means, about to be described, are provided for holding the inner roller 45 raised during this pause. It is not necessary to raise the outer roller 45, as the inner roller 45 is lowered quickly enough to remove the heavier ink zone left on the type by the outer roller.

As shown in Fig. 1, the shaft 81 of the printing roller 14 rotates in vertically guided slidable bearing blocks 82 for said roller at the ends thereof; and means, later to be described, are provided for raising each block 82 and consequently the roller 14, when the bed moves outwardly, to prevent the roller from dragging on the type.

Means is provided for raising the form roller 45 nearest the printing roller as the bed moves outwardly and pauses at its outward limit, to prevent excessive ink from such roller at such time, said means lowering such roller as soon as the bed begins to move inward. This means is here shown, by way of example, as operated from the blocks 82, and comprises vertical slide rods 83, 84 carried by each bearing block 82 on opposite sides of the printing roller shaft, the rod 83 carrying a lateral bracket 85 (Fig. 9), in turn carrying a vertical push rod 86 having a flat head 87 engaged under the journal block 41 of the form roller 45 nearest the printing roller, whereby when the roller 14 is raised the inner roller 45 is raised also.

The means for raising the printing roller is here shown as comprising at each end of the roller, an upright toggle 90, 91 under each block 82 having its upper end pivoted to the block and the lower end pivoted to the frame 10. A link 92 has one end connected to the toggle joint of the toggle and the other provided with a roller engaging in a cam groove 94 in a rotary disk cam 95 on the frame thereby to reciprocate the roller, link and toggle joint, thereby to raise the printing roller as the bed moves outwardly. The shape of the groove 94 is such that said control means holds the inner form roller 45 raised during the pause of the bed during its reversal at its outward limit, thereby to prevent the causing of an ink stripe by the inner roller during the pause, and such that the control means lowers said inner form roller 45 to the type before any ink stripe which may be caused by the outer roller 45 reaches the inner roller, thereby to cause the inner roller to erase such stripe.

I claim as my invention:

1. In combination, a reciprocatory bed having a rack longitudinal to the path of the bed; an inking device comprising a pair of bearing brackets on opposite sides of said path; parallel form rollers having roller end shafts mounted in the

brackets; a large stationary tubular bearing member mounted and spaced coaxially around the adjacent end one of the roller shafts; a ring gear rotatably received on said bearing member meshing with said rack; a distributor roller resting on said form rollers and provided with end shafts rotary in the upper part of said bearing brackets, one end of said vibrator having a gear meshing with said ring gear, and means for causing endwise reciprocation of the vibrator when rotated back and forth.

2. In combination, a frame; a printing roller on the frame adapted to receive paper carried around the roller in one direction; a bed reciprocatory to bring the type thereon into engagement with the paper when the bed moves inwardly; vertically guided slidable bearing blocks for said roller at the ends thereof; means for raising each block and consequently the roller when the bed moves outwardly, inking rollers near one side of the printing roller for engaging type on the bed when the bed is at inward position, a supplemental inking device near the other side of the printing roller comprising a pair of brackets on opposite sides of the frame, each bracket having guide slots; journal blocks vertically adjustable in said slots respectively; parallel form rollers having shafts mounted in the blocks; and means operated, from said bearing blocks for raising the form roller nearest the printing roller as the bed moves outwardly and pauses at its outward limit, to prevent excessive ink from such roller at such time, and lowering such roller as soon as the bed begins to move inward.

3. In a combination as in claim 2, said last named means comprising vertical slide rods carried by each bearing block on opposite sides of the printing roller shaft and guided at the lower ends in the frame; a bracket on the rod nearest the form rollers; and a push rod carried by said bracket and having a flat head engaged under the journal block of the form roller nearest the printing roller.

4. In a combination as in claim 2, said means for raising the printing roller comprising an upright toggle at each block having its upper end pivoted to the block and the lower end pivoted to the frame; a link having one end connected to the toggle joint of each toggle and the other provided with a roller; and rotary disks on the frame and each provided with an eccentric cam groove to receive and reciprocate the roller, link and toggle joint thereby to raise the printing roller as the bed moves outwardly and during said pause.

5. An attachment for a printing press having a frame and a type bed movable thereon and having an upper rack; comprising a pair of like spaced companion ink distributing rollers engageable with the bed; a rotatable endwise movable roller having a diameter different from that of the first rollers and engaging the latter, said endwise movable roller having thereon and aligned with the periphery thereof an elongate gear, a tubular bearing fixed on the frame concentric with one of the distributing rollers and having a diameter equal thereto, and a ring gear freely mounted on said bearing and meshed with said rack and with the first gear.

THOMAS PADULA.
